UNITED STATES PATENT OFFICE.

FREDERICK S. STRONG, OF EAST BRIDGEWATER, MASSACHUSETTS, ASSIGNOR
TO THE CARVER COTTON GIN COMPANY, OF SAME PLACE.

SOLE-LEVELING MACHINE.

SPECIFICATION forming part of Letters Patent No. 403,495, dated May 14, 1889.

Application filed December 24, 1888. Serial No. 294,524. (No model.)

To all whom it may concern:

Be it known that I, FREDERICK S. STRONG, of East Bridgewater, in the county of Plymouth and State of Massachusetts, have invented certain new and useful Improvements 5 in Sole-Leveling Machines, of which the following, taken in connection with the accompanying drawings, is a specification.

The object of my invention is to so improve 10 the construction of sole-leveling machines as to insure a more even pressure of the pressure or leveling roll on all parts of the sole, and also to so arrange the parts that, although the extreme end of the toe of the sole will receive 15 the full pressure, the movement of the pressure-roll is so guided that it cannot injure this part by abruptly leaving it or by striking it on the return-stroke.

My invention also relates to some of the 20 minor devices of the machine, which may be best understood by reference to the drawings and specification. These objects I attain by the mechanism shown in the accompanying drawings, in which—

25 Figure 1 is a side elevation of a leveling-machine with my improvement embodied. Fig. 2 is a view showing most of the parts in side elevation and some in longitudinal vertical section. Fig. 3 is a plan showing a detail 30 vice for reversing the motion of the shoe-holding jack. Fig. 4 is a view in elevation and section showing a device connected to the reversing-lever for the purpose of holding the reversing-lever in such a position that the jack will remain stationary. Fig. 5 is a 35 plan showing the leveling-roller and its adjuncts. Fig. 6 is a view showing, partly in elevation and partly in section, the device by which a spring or yielding pressure is brought 40 to bear on the leveling-roller. Fig. 7 is a diagram intended to illustrate the operation 45 of the leveling-roller in relation to the shoe.

In the drawings, Figs. 1 and 2, A represents 50 the frame of the machine, and B, Figs. 1, 2, and 3, the main shaft of the machine, which has upon it fast and loose pulleys (see Fig. 3) for connecting it with the motive power.

B', Fig. 1, is a balance-wheel attached to

the main shaft B. This wheel B' has upon it 50 (see Fig. 1) ways B², in which a crank-pin plate, B³, is adapted to slide and to be fixed at any desired position by suitable set-screws. Upon the plate B³, I have a crank-pin, B⁴, which as the wheel B' rotates gives motion to 55 the link B⁵, which in turn moves the arm B⁷, attached to the rocker-shaft B⁸. From the rocker-shaft B⁸ arms B⁹ extend, Figs. 2 and 5, and are connected at their tops by pins B¹⁰ to links B¹¹. The links B¹¹ B¹¹, Fig. 5, have at 60 their outer ends holes through which the shaft B¹³ passes. The shaft B¹³ carries the leveling-roller B¹², and is guided by sliding boxes B¹⁴ B¹⁴, in which its ends rest. The boxes B¹⁴ B¹⁴ slide in ways b b, made on the 65 inner faces of the frame C.

The frame C swings on pins C' in the frame A, Figs. 1 and 2. Pressure is exerted on the frame C, and through it onto the leveling-roller B¹², by means of rods C⁴ and the foot-lever C¹⁰. To obtain an adjustable yielding tension on the frame C, I have the following-described device, (see Figs. 2 and 5.)

C² is a swiveling cross-bar, the ends of which are attached to the frame C. Through 75 the cross-bar C² rods C⁴ pass. The upper ends of these rods have gear-wheels C¹³ C¹³. C¹⁴ is a gear-wheel engaging with the gears C¹³ C¹³, and is actuated by the hand-wheel C¹⁵. The lower ends of the rods C⁴ C⁴ (see Fig. 6) 80 are screwed into cross-bars c. Each of the cross-bars c has two rods, c' c', which in turn are attached at their lower ends to a cross-bar, c². Between the cross-bar c² and the top of the cylinder C⁵, I place a compressed spring, c³. The lower ends of the cylinders C⁵ are attached to cross-bar C⁷, which is connected to the foot-lever C¹⁰ by means of a pin, C⁸, and block C⁹. The foot-lever C¹⁰ is pivoted to the frame at C¹¹, Fig. 2, and has a counter-weight, 90 C¹². The intensity of the spring c³ may be adjusted by turning the rods C⁴ so as to compress it more or less. (See Fig. 6.) The springs c³ have no effect on the frame C or through it on the leveling-roller B¹², except when the foot-lever C¹⁰ is brought down. Then the pressure 95 exerted by the operator on the leveling-roller B¹² will be governed by the expansive force

of the springs c^3 , which may be lessened or increased by turning the rods C^4 by means of the hand-wheel C^5 , as has been set forth.

The shoe to be operated upon is mounted 5 on the jack K^6 and toe-support K^6 , Figs. 1 and 2, which are in turn supported on the laterally-swinging frame K . The swinging frame K is hung at each end on pivots $H^4 H^5$, connected with the longitudinally-oscillating frame $H H' H^2$, and can be operated by the hand-lever K^4 , shaft K^8 , arm K^2 , and pin K' . The oscillating frame $H H' H^2$ swings on a pivot, H^3 , and is operated by power through the oscillating screw-nut E (connected by the bracket E^4 and bolt E^6 to the lower part, E^3 , of the frame $H H' H^2$) and the screw-shaft E^7 E^{10} . The screw-shaft $E^7 E^{10}$ is supported at its upper end in a laterally-sliding housing, D^3 , mounted on the rod D^4 , (see Figs. 2 and 3,) and is driven by the friction-cone D^2 , which is made to engage either with the friction-cone D or D' by the operator, as he may wish to turn in one direction or the other.

The device for causing the friction-cone D^2 to engage either with the friction-cone D or D' consists in a link, D^5 , Fig. 3, a bent lever, D^6 , pivoted to the frame of the machine at D^7 , a link, D^9 , pivoted to the bent lever D^6 at D^8 , and to the hand-lever D^{12} at D^{10} , (see Figs. 2 and 3,) the whole being operated by the hand-lever D^{12} , it being provided with a handle, as shown at D^{13} , Fig. 2.

It may be understood from the above that as the screw-shaft $E^7 E^{10}$ rotates in one direction the screw-nut E will cause the entire frame $H H' H^2$, together with the jack-frame K and jack and shoe, to oscillate in a corresponding direction—that is, in the direction indicated by the arrow t in Fig. 7, or opposite to it, as the case may be—and that the rotation of the shaft $E^7 E^{10}$ is caused by the action of one of the friction-cones D or D' on the friction-cone D^2 .

To prevent the screw-shaft $E^7 E^{10}$ from moving the frame $H H' H^2$ too far, I have an automatic stopping device for acting on the sliding housing D^3 , and so moving it as to move the friction-cone D^2 into the position shown in Fig. 3, in which it touches neither of the driving friction-cones D or D' . This device consists of a rod, L , attached to the frame $H H' H^2$ at L' , and having on it two stops, $L^2 L^3$, which are so located in relation to an arm, D^{11} , on the rod D^9 that when the frame $H H' H^2$ has oscillated as far in either direction as it is desirable to have it then one or the other of the stops $L^2 L^3$ will come in contact with the arm D^{11} of the rod D^9 and cause it (acting through the bent lever D^6 , link D^5 , and housing D^3) to move the friction-cone D^2 out of contact with either of the driving friction-cones D or D' , and thus stop all further movement of the frame $H H' H^2$.

The lever D^{12} , that operates the stopping-rod D^9 , (see Fig. 4,) is so connected with an automatic spring device that it will, when not actuated by the operator, stand in such a po-

sition as to keep the friction-cone D^2 out of contact with the driving friction-cones D and D' . This device consists of a flat plate, M , 70 Fig. 4, which is pressed by a strong spring, M^2 , in a case, A^3 , attached to the frame of the machine against the flat end or bottom of the lever, so that the whole tendency of the spring M^2 is to keep the stopping-lever D^{12} in its normal position. The pin D^{14} upon which the lever D^{12} swings is fixed in the frame. 75

To prevent injury to the power-oscillating device of the frame $H H' H^2$, I place on the screw-shaft $E^7 E^{10}$ a spring-bumper, E^8 , Fig. 2, 80 guided by two rods, $e e$, connected to the plate E^9 , the bumper E^8 being made yielding by the spring e' .

The downward limit of the field of action of the leveling-roller B^{12} is determined by the 85 adjustable head-block N' , Fig. 1, which serves as a stop or resting-point for the boss N^8 on the frame C , and as the frame C limits and controls the field of action of the roller B^{12} it is evident that the position of the head-block N' determines the plane of action of 90 the roller B^{12} . The head-block N' is fixed to the top of the standard N , Fig. 1, by being screwed onto it like a nut, and is held firmly by a check-nut, N^2 . The standard N is made 95 fast to the frame A by the bolt N^4 .

In Fig. 7 the position of the shoe and the line of motion which is given to it by the oscillating frame $H H' H^2$ is illustrated by the curved line $r r$, indicating the path of the 100 sole of the shoe—that is, the shoe moves in an arc, the center of which is at H^3 —so that the leveling-roller B^{12} exerts almost the same pressure on all parts of the sole, the pressure being the same at the shank and toe and but 105 slightly increased on the ball. The extreme lowest plane that the leveling-roller B^{12} can work in is determined by the position of the adjustable head-block N' , which should be so set as to admit of the leveling-roller B^{12} to 110 fall but a trifle below the surface of the sole as it passes off from the toe, and to again pass onto the sole without abruptly coming in contact with the end of the sole. This device for controlling the line of motion of the sole of the 115 shoe and the plane of action of the leveling-roller B^{12} insures an even pressure on all parts of the sole, and effectually guards against injury to the toe of the sole as the leveling-roller passes onto it or off from it. 120

I am aware of the patents to Othniel Gilmore, dated October 24, 1882, No. 266,283, and June 29, 1886, No. 344,650, and do not claim anything therein disclosed.

I claim—

1. In a shoe-sole-leveling machine, the combination of a jack for holding the shoe and adapted to oscillate in a path the line of which lies in a circular arc coinciding practically with the arc of the sole of the shoe, 130 with a leveling-roller, B^{12} , frame C , and adjustable head-block N' , substantially as described, and for the purpose set forth.

2. In a shoe-sole-leveling machine, the com-

bination of the oscillating frame H H' H², oscillating nut E³, screw-shaft E⁷ E¹⁰, and sliding housing D⁸, with the friction-cone D², adapted to be actuated by the driving friction-cones D D', substantially as described, and for the purpose set forth.

3. In a sole-leveling machine, the combination of the shaft E⁷ E¹⁰, sliding housing D⁸, link D⁵, bent lever D⁶, and shipping-rod D⁹, with the hand-lever D¹², spring-plate M, and spring M', all operating together substan-

tially as described, and for the purpose set forth.

In testimony whereof I have signed my name to this specification, in the presence of two subscribing witnesses, on this 20th day of December, A. D. 1888.

FREDERICK S. STRONG.
